UNITED STATES PATENT OFFICE.

THOMAS B. ATTERBURY, OF PITTSBURG, PENNSYLVANIA.

MANUFACTURE OF GLASS ARTICLES.

SPECIFICATION forming part of Letters Patent No. 275,564, dated April 10, 1883.

Application filed February 13, 1883. (No model.)

To all whom it may concern:

Be it known that I, THOMAS B. ATTERBURY, a citizen of the United States, residing at Pittsburgh, in the county of Allegheny and State of Pennsylvania, have invented certain new and useful Improvements in Manufacture of Glass Articles; and I do hereby declare the following to be a full, clear, and exact description of the invention, such as will enable others skilled in the art to which it appertains to make and use the same.

My invention relates to the manufacture of glass vessels provided with a guard, cap or flange which partially incloses the upper portion of the cavity, to prevent the contents of the vessel from coming in contact with the mustache, to hold back the froth or foam of aerated or malt liquors, and also to prevent the ice which may be in the vessel from being poured out or from coming in contact with the lips of the person drinking from such vessel.

To this end my invention consists in pressing the main body of the article in one piece or section, providing it with offsets or "marees" to receive the guard or flanged portion, which is pressed in a separate mold and joined to the main body while at a welding-heat.

In a separate application filed by me January 20, 1883, Serial No. 82,446, I formed the main body of the article, together with the guard or flange, at one and the same operation of pressing, and subsequently reheated and folded the flange or guard down over the top of the article while at a welding-heat and joining it thereto, so as to form a guard or flange.

In this invention I employ essentially the same process shown and described in Letters Patent No. 181,618, granted to me August 29, 1876, but with such changes and modifications as will produce the article desired, whether it be a beer-mug, goblet, pitcher, or other article requiring a guard or flange to regulate the flow of the liquids therefrom, or to prevent certain portions of the contents from being poured from the vessel.

Referring to the drawings, Figure 1 is a sectional view of the mold with the plunger and article therein. Fig. 2 is a sectional view of the mold for forming the guard or flange. Fig. 3 is a side elevation of the bottom of the flange or guard forming mold. Fig. 4 is a top or

plan view of the article with the guard or flange thereon.

A A indicate the sections of an ordinary two-part mold in which the article is pressed, 55 and I may have the mold-cavity of any desired configuration.

B is the mold or plunger ring, of the usual or of any desired form, on the under side of which is formed one or more segmental flanges, 60 a, which forms in the inner upper edge of the cavity of the article recesses or marees b, to receive the guard or flange, made with special reference to fill such marees and afford a perfect seat for said guard or flange. 65 ..

C is the plunger, of the ordinary or any desired construction, operated by any of the well-known power or hand presses.

D is the mold for forming the guard or flange, and may be of any suitable or convenient construction. In the present instance, however, I have shown the mold-cavity of semi-cylindrical form in cross-section, with a plunger, E, having on its lower end projections and cavities which will give the proper 70 form to the guard or flange, as shown at e, Fig. 4. In practice, however, I may make the mold-cavity of the shape which is desired to be given to the flange or guard, and then make the plunger to conform to said cavity. 75 ..

In Fig. 4 I have shown a top or plan view of a beer-mug or handled glass made in accordance with my invention. F indicates the body of the article, and e the flange or guard joined thereto, while the dotted lines show the 85 depth of the offsets or marees, into which is fitted the ends of the guard or flange. The main body of the article and the guard or flange are made in the usual manner, and at or about the same time. The guard or flanged 90 portion is then removed from its mold while still at a welding-heat, and adjusted in position in the offsets or marees formed in the main body of the article, when the two sections will unite, forming a tight joint. If necessary, a 95 tool is passed rapidly over the joints with light pressure to insure a more perfect union of the parts.

I do not wish to limit myself to the manufacture of beer-mugs, goblets, glasses, or other 100 drinking-vessels, as it is obvious that water-pitchers, molasses-pitchers, cream-jugs, gravy-

dishes, and an endless variety of articles can be produced with a guard or flange in accordance with my invention.

The main body of the article may be pressed 5 without the offsets or marees, and the upper edge made perfectly plain, to which the guard or shield flange is attached at a welding-heat, and finished by tools and fire-polishing. In either instance, or by whichever method made, 10 the guard or shield flange *c* is cut away or formed with a recess at its outer edge to form a pouring or drinking orifice, *c'*, as shown in Fig. 4.

Having thus described my invention, what I 15 claim, and desire to secure by Letters Patent, is—

1. As an improvement in the manufacture of glass vessels having guard or shield flanges, forming the article in sections in separate 20 molds, and then joining the sections while at a welding-heat to cause them to unite, as set forth.

2. As an improvement in the manufacture of glass vessels or articles having guard or

shield flanges, forming the article in sections in separate molds, the main body of the article being formed with offsets or marees to receive the guard or shield flange, the sections being united while at a welding-heat, as set forth. 25

3. As a new article of manufacture, a glass 30 vessel having a shield or guard flange made separately from and joined to the main body of the article while at a welding-heat, as set forth.

4. A glass vessel or other article the main 35 body of which is formed with offsets or marees to receive a guard or shield flange, said flange being provided with a drinking or pouring orifice, and the two sections being united at a welding-heat, as set forth. 40

In testimony whereof I hereby affix my signature in presence of two witnesses.

THOS. B. ATTERBURY.
